FOOT OPERATED ELECTRIC SWITCH

Harry A. Douglas, Bronson, Mich.

Application January 18, 1934, Serial No. 707,132

27 Claims.

(Cl. 200—18)

This invention relates to improvements in electric switches and more particularly to switching mechanism including a reciprocable actuating means adapted to be foot operated to alternately 5 continue and discontinue different circuits passing therethrough.

It is an object of this invention to provide a simplified and economical structure which will be positive in operation and which will withstand 10 the rough usage to which a foot operated switch is subjected. It is a further object to provide an electric switch of this type which is of particular advantage for controlling the bright and tilt filaments of motor vehicle headlights.

15 The advantages of such a switching mechanism are obvious, when employed in connection with a main hand operated switch in the lighting system of an automobile, such as disclosed in this applicant's prior copending application, Serial No. 696,445 filed November 2, 1933, in which the driver of the automotive vehicle having set his headlights in the bright position is able by a slight movement of his foot, upon approaching a car traveling in the opposite direction, to dim his bright lights without removing his hand from 25 the steering wheel.

With these and other objects in view, reference is made to the accompanying sheets of drawings which illustrate an embodiment of this invention, 30 with the understanding that detail changes may be made without departing from the scope thereof.

In the drawings—

Figure 1 is a view in central vertical section, 35 illustrating a preferred embodiment of this invention, showing one circuit closed.

Figure 2 is a view in vertical section taken on the line 2—2 of Figure 1, looking in the direction of the arrows.

40 Figure 3 is a view in transverse section taken on the line 3—3 of Figure 1, looking in the direction of the arrows.

Figure 4 is a view in transverse section taken on the line 4—4 of Figure 2, looking in the direction 45 of the arrows.

Figure 5 is a view similar to Figure 1, illustrating the position of the parts having opened one circuit and about to close the other.

Figure 6 is a fragmentary detail view in vertical section taken on the line 6—6 of Figure 1, looking in the direction of the arrows.

Figure 7 is a fragmentary detail view in vertical section taken on the line 7—7 of Figure 1, looking in the direction of the arrows.

55 Figure 8 is a detail projected view in perspective

tive of a circuit continuing member and its support.

Figure 9 is a similar view of the actuator and its support.

This invention, as illustrated, includes a cylindrical metallic casing 1 mounting at one end a plunger cap 2, surrounding an elongated restricted portion 3 of the casing, and adapted to reciprocate thereover. The casing is closed at the other end by a contact carrier 4 of insulating material. It is preferable to increase the diameter if the open end receiving the contact carrier and fold the metal back on itself to form an annular flange 5 adapted to be engaged by a mounting plate 6, perforated to snugly receive the casing, 15 and the body of the casing therebelow again increased in diameter to form a shoulder 7 to engage the underside of the plate 6 and secure the casing thereto. It is preferable to depress the body of the plate 6 about the casing receiving 20 opening, as shown, so that the upper surface of the plate will lie flush with the upper surface of the flange 5 and also provide the casing receiving opening with a radial notch 8 into which the body 9 of the casing below the flange is 25 forced to enter to retain the casing against rotation. The contact carrier 4 is preferably in the form of a disc snugly received within the open end of the casing 1 and held in engagement with the underside of the mounting plate holding 30 shoulder 7 by a circular closure plate 10, of greater diameter than the outer diameter of the casing provided, with preferably three unequally spaced apart circumferential notches 11 for receiving similarly disposed fingers 12 depending 35 from the lower end of the casing, the ends of which are adapted to be bent inward to engage the outer surface of the plate 10 and secure the same to the casing below the mounting plate 6. The closure plate 10 is preferably of insulating 40 material.

The contact carrier disc mounts three electrical connectors with their centers in line, with the center of one in the axis of the casing 1 and the other two equidistant therefrom. The center connector is in the form of an elongated rectangular metallic bar 13 passing through a rectangular aperture provided therefor in the contact carrier 4 and the closure plate 10, extending approximately an equal distance on each side 50 thereof with that portion entering the interior of the casing 1 of slightly greater width to form shoulders resting upon the inner surface of said carrier and projecting at right angles therefrom. The connector 13 is preferably held in place by 55

a rectangular block of insulating material 14 in engagement with the exterior side of the closure plate 10 and the contiguous depending side of the connector, the lower ends of both connector 5 and block being apertured to receive a metallic snap terminal electrical connector block, preferably of the type disclosed in this applicant's prior copending application, Serial No. 565,127, filed September 25, 1931, including a rectangular portion 15 having a cylindrical projection 16 adapted to pass through the block 14 and bar 13 with the metal of the end 17 projecting therebeyond spun or riveted to engage the outer surface of the bar and not only hold the block in place but 10 also make an electrical connection to said bar. The connectors 18 and 19, arranged equidistant from the axis of the casing, are preferably of the same type as above described having the rectangular portion passing through rectangular 15 apertures provided therefor in the closure plate 10 and the cylindrical portion passing through cylindrical apertures in the contact carrier 4. The inner ends of connectors 18 and 19 pass through the bases 20 of similar right angular 20 brackets having arms 21 extending parallel and equidistant from the bar 13 upon the interior of the casing, with the metal of the end 17 spun or riveted upon the interior surfaces of said bases to not only hold the brackets in place, but also 25 to make an electrical connection therewith. As shown in Figures 1 and 4, the rectangular portion of the connector 19 is in engagement with the adjacent surface of the block 14 and positions the upper end thereof.

Means is provided for alternately continuing the circuit from the bar 13 to the contacts 17 carried upon the connectors 18 and 19 which includes a current continuing member or bridge mounted for oscillation upon each bracket arm 40 21 and an actuator cooperating therewith. The current continuing members 22 are each elongated rectangular metallic plates having oppositely disposed integral ears 23 extending intermediate one side thereof and at right angles thereto and with one end 24 bent at right angles in the same direction and for the same distance as the ears 23. The current continuing members 22 are of the same width as the bracket arms 21. Each ear 23 is provided with a rectangular 45 slot with the end adjacent the body forming a reentrant angle with its apex in the center thereof forming a knife-edge bearing 25. Each arm 21 is provided with oppositely disposed lateral projections 26 equidistant from the upper end thereof which projections are adapted to be embraced by the ears 23, being received within the slotted portion and adapted to bear against the knife-edge bearings 25, when assembled, with the right angle end portions 24 passing freely above the upper ends of the arms 21. The members 22 may be oscillated about the bearings 25 and when moved in one direction the extremity of the portions 24 will engage the upper part of the connector 13 and when moved in the opposite direction, the opposite end of the member 22 50 will engage the arm 21 below the ears 23.

An actuator for oscillating the current continuing members 22 in unison to alternately cause the portions 24 to contact the connector 70 13 and maintain the said contact until operated to oscillate in the opposite direction includes a plate 27 of insulating material preferably in the form of a circular disc of less diameter than the inner diameter of the casing 1 with oppositely disposed portions cut away equidistant from the

center to form parallel sides 28. The body of the actuator 27 is cut out to form a rectangular opening with its diametrical center concentric with the center of the disc and its longest sides 29 parallel to the flat sides 28 of the actuator 5 and sufficient distance apart to receive the circuit continuing members 22, which parallel sides are each provided with centrally disposed inwardly extending lugs 30. The sides of the connector bar 13 are provided with oppositely disposed cut out portions 31, in line with the lateral projections 26 of the arms 21, adapted to receive the lugs to support the actuator and allow oscillation of the actuator about said lugs. The bracket arms 21 are resilient and the sides 29 of 10 the opening in the actuator are of such dimensions that when assembled, as shown in Figure 5, the body of the actuator engages the members 22 and through the knife-edge bearings 25 and projections 26 of the arms 21 place said arms 20 under tension by forcing the upper ends thereof toward each other when the actuator is in parallel relation to the contact carrier 4, as shown in Figure 5. It is therefore seen that upon rotative movement of the actuator the tension of the 25 arms 21 immediately snaps the actuator off center, causing one end to move upward in sliding engagement with the adjacent member 22 rotating the same about the knife-edge 25 until the end of the portion 24 contacts the bar 13, and 30 at the same time causing the other end of the actuator to move downward in sliding engagement with the other member 22 rotating it about its pivot 25 and concurrently causing the lower end of said member to engage the arm 21 there- 35 below. In this position, the engagement of the portion 24 with the bar 13 is maintained by the resistance of the resilient arms 21 to any movement of the actuator in the opposite direction. The actuator carries an operating bracket to 40 cooperate with a reciprocable plunger as herein-after described. The actuator operating bracket is preferably of metal and formed to provide a horizontal portion over the opening in the actuator plate and positioned thereover to clear 45 the upper end of the bar 13, when assembled, by oppositely disposed integral depending sides 32 having reduced portions 33 adapted to be received in recesses 34 in the sides 28 of the actuator which portions are continued at each edge 50 into fingers 35 adapted to be bent inwardly to engage the underside of the actuator plate 27 with the shoulders formed by the reduced portions in engagement with the upper side of said actuator, as shown in Figures 2, 6, 7 and 9. The 55 upper surface of the bracket above the axis of rotation of the actuator is depressed on each side thereof to form oppositely and downwardly extending angular surfaces 36 and 37 forming an obtuse angle with its apex parallel with the axis of rotation of the actuator and with the lower and exterior ends of said surfaces continued beyond the arms 32 and curved upwardly tangential to said surfaces to form stops 38 equidistant from the actuator.

The actuator is caused to oscillate by the reciprocation of a plunger 39 mounted to travel within the restricted portion 3 of the casing 1, the upper end of which plunger is secured to the closure of the plunger cap 2. The portion of 70 the plunger at all times contained within the restricted casing 3 is preferably rectangular and is provided with a reduced portion secured to the cap 2. The metal about the open end of the reduced casing 3 is turned inwardly to en- 75

gage the shoulders so formed and limit the upper movement of the plunger. The plunger is normally maintained in its extended position or at the upper limit of its travel by a coil spring 40 surrounding the restricted casing 3 with one end in engagement with the closure of the cap 2 and the other end in engagement with the shoulder provided by reducing the diameter of the casing 1 to form the restricted casing 3. The plunger is preferably provided with an axial bore 41 terminating adjacent the upper end thereof and with a transverse slot forming spaced apart depending legs 42 in the portion of greatest width. A depending operating finger 43 of insulating material is pivotally mounted adjacent its upper end within the slot by a pin 44 passing therethrough and through both of the legs 42. A spring pressed detent 45 is mounted within the slot above the top of the operator 43 having a guide pin 46 and spring 47 received within the bore 41 and normally maintains the operator 43 in axial alignment with the axis of the casing 1. The nose of the operator 43 is normally held by the plunger cap spring 40 in axial alignment above the upper surface of the actuator operating bracket and, as shown in Figure 1, above one of the sloping surfaces 36 or 37 thereof. Upon depression of the plunger cap the operator 43 engages the adjacent sloping surface, slides thereover as it is rotated about its pivot 44 until it engages a stop 38, as shown in Figure 5, placing the arms 21 under greater tension until the actuator plate 27 is carried off center in the opposite direction to establish and maintain a circuit from the bar 13 through one current continuing member 22. Upon release of the plunger cap 2 the spring 40 returns the plunger 39 and operator 43 to the normal position, so that upon a further reciprocation the actuator 27 is oscillated in the opposite direction to discontinue the circuit just described and establish a circuit through the other current continuing member 22.

What I claim is:

1. An electric switching mechanism including a contact carrier, an electrical connector mounted on said carrier, and oppositely disposed electrical connectors mounted on said carrier equidistant from said first connector, current continuing members mounted for oscillation upon each of the last named connectors, an actuator mounted to oscillate upon the first named connector, means provided upon the actuator to oscillate the current continuing members in unison upon oscillation of the actuator to engage one and disengage the other of the current continuing members alternately with the first mentioned connector, and operating means to oscillate the actuator.

2. The structure of claim 1 wherein the actuator includes an operating bracket mounted thereon over the connectors and current continuing members cooperating with the operating means.

3. The structure of claim 1 wherein said operating means includes a reciprocating plunger and wherein the actuator includes an operating bracket mounted thereon over the connectors and current continuing members cooperating with each reciprocation of the plunger to oscillate the actuator.

4. The structure of claim 1 wherein said operating means includes a plunger mounted for reciprocation in line with the first named connector and having a depending operating finger pivotally carried therein and wherein the ac-

tuator includes an operating bracket provided with oppositely disposed stops to be engaged by the pivoted operator upon reciprocation of the plunger to oscillate the actuator.

5. The structure of claim 1 wherein the contact carrier is of insulating material and oppositely disposed connectors are provided with right angular bases resting upon the interior surface of the contact carrier and are secured thereto by electrical connectors passing from the outer side of the carrier through the carrier of the base.

6. The structure of claim 1 wherein the contact carrier is of insulating material and the first named connector is in the form of a flat shouldered metallic bar passing through the carrier with the shoulders engaging the inner side thereof and the portions on the other side secured by a block of insulating material in engagement with that side of the carrier and the contiguous surface of the bar with the block secured to the bar by an electrical connector passing through the block and bar.

7. The structure of claim 1 wherein the contact carrier is of insulating material and oppositely disposed connectors are provided with right angular bases resting upon the interior surface of the contact carrier and are secured thereto by electrical connectors passing from the outer side of the carrier through the carrier and base, and wherein the first named connector is in the form of a flat shouldered metallic bar passing through the carrier with the shoulders engaging the inner side thereof and the portion on the other side secured by a block of insulating material in engagement with that side of the carrier and the contiguous surface of the bar with the block secured to the bar by an electrical connector passing through the block and bar at the lower ends thereof with the upper end of the block positioned by the exterior of a connector secured to one of the oppositely disposed connectors.

8. An electric switching mechanism including a contact carrier, an electrical connector mounted on said carrier and oppositely disposed resilient electrical connectors equidistant from the first connector mounted on said carrier, current continuing members mounted for oscillation upon each of the last named connectors, an actuator mounted to oscillate upon the first connector, means provided upon the actuator to oscillate the current conducting members in unison upon oscillation of the actuator to alternately engage and disengage the current conducting members with the first connector and place the resilient connectors under tension maintaining the electric contact established at each end of oscillation of the actuator, and operating means to oscillate the actuator.

9. An electric switching mechanism including a contact carrier, a rigid electrical connector mounted on said carrier and oppositely disposed resilient electrical connectors equidistant from the first carrier, current continuing members mounted for oscillation upon each of the last mentioned connectors, an actuator mounted to oscillate upon the first connector having its axis of oscillation in line with the axes of oscillation of the current conducting members, means provided upon the opposite ends of the actuator to oscillate the current continuing members in unison upon oscillation of the actuator to alternately engage and disengage the current continuing members with the first connector and place the

resilient connectors under tension maintaining the electric contact established at each end of oscillation of the actuator when the actuator is moved off center, and operating means to oscillate the actuator.

10. The structure of claim 9 wherein the current continuing members include metallic plates provided with bearing members engaging the outer sides of the resilient connectors and angular end portions passing over the upper extremities of said connectors.

11. The structure of claim 9 wherein the current continuing members include metallic plates provided with bearing members engaging the outer sides of the resilient connectors cooperating with means upon said connectors preventing longitudinal movement thereof and provided with angular end portions passing over the upper extremities of said connectors to contact the rigid connector and limit the movement about the pivoted point in that direction.

12. The structure of claim 9 wherein the actuator includes a plate of insulating material embracing the connectors and having sliding engagement with the current continuing members.

13. The structure of claim 9 wherein the actuator includes a plate of insulating material cut out to embrace the connectors and current continuing members and having sliding engagement therewith.

14. The structure of claim 9 wherein the actuator includes a plate of insulating material cut out to embrace the connectors and have a sliding engagement with the current continuing members provided with bearing members upon the inner walls engaging the rigid connector.

15. In a foot operated electric switch, a cylindrical casing having an elongated reduced portion at one end with a spring pressed plunger cap mounted thereon and adapted to be reciprocated over said casing, a contact carrier closing the other end, a rigid metallic connector mounted axially of the carrier extending within the casing, resilient connectors mounted upon the carrier extending within the casing equidistant from opposite sides of the rigid connector and normally parallel therewith, current continuing members mounted for oscillation about the outer faces of the resilient connectors, an actuator of insulating material surrounding said connectors and current continuing members mounted for oscillation about the rigid connector with its axis of oscillation in the same plane as the axes of oscillation of the current continuing members having sliding engagement with said members and when parallel with the contact carrier placing the resilient connectors under tension, a reciprocable plunger secured to the cap closure guided within the restricted casing for axial movement, a pivotally mounted operator depending normally in axial alignment from the plunger, and means upon the actuator above the connectors cooperating with the operator to oscillate the actuator upon depression of the plunger to bring one current continuing member in contact with the rigid connector and the other in additional engagement with its supporting resilient connector and place both resilient connectors under tension.

16. The structure of claim 15 wherein the current continuing members are flat metallic plates having inturned upper ends with the flat portions positioned parallel to each other when the actuator is parallel to the contact carrier and positioned with one inturned end of one in con-

tact with the rigid connector and the lower extremity of the other in engagement with its supporting connector when the actuator is at the ends of its oscillations.

17. The structure of claim 15 wherein the current continuing members are flat metallic plates having inturned upper ends with the flat portions positioned parallel to each other when the actuator is parallel to the contact carrier and positioned with one inturned end of one in contact with the rigid connector and the lower extremity of the other in engagement with its supporting connector when the actuator is at the ends of its oscillations, the tension of the resilient connectors acting through the current continuing members whenever the actuator is moved off center therewith by the operator to snap the actuator to the end of its oscillations.

18. The structure of claim 15 wherein the said cooperating means upon the actuator includes an extension thereabove having oppositely disposed sloping surfaces terminating in stops to be alternately engaged by the operator upon continued reciprocation of the plunger.

19. An electric switch, comprising: a first oscillating switch member; a second oscillating switch member; a single cooperating terminal means; and actuator means, connected to said switch members to move said members simultaneously, one of them in a direction into contact with said terminal means and the other one in a direction out of contact with said terminal means.

20. An electric switch, comprising: a casing; a mounting plate for said switch, provided with an aperture through which said casing extends; said casing being provided on both sides of said mounting plate, with flanges overlying said mounting plate to connect said mounting plate to said casing and means for locking said casing and mounting plate against relative rotation.

21. An electric switch, comprising: an insulating base; a terminal, projecting through an aperture in said base and provided with a shoulder engaging the inner face of said base; and an insulating member secured to said terminal exteriorly of said base and abutting said base to hold said terminal against movement inwardly of said base.

22. An electric switch, comprising: a first oscillating switch member having different limiting positions; a second oscillating switch member having different limiting positions; actuator means, connected to said switch members to move said members; and means whereby said actuator means cooperates with said switch members to bias one of said switch members to one of its limiting positions while biasing the other of said switch members to a different one of its limiting positions.

23. An electric switch, comprising: a first oscillating switch member; a second oscillating switch member; said switch members being mounted for movement about parallel axes; and actuator means, connected to said switch members to move said members about said axes in the same direction with said actuator means moving in a predetermined direction.

24. An electric switch, comprising: a base; switch actuating mechanism unitary with said base; a casing for said switch actuating mechanism; operating mechanism, unitary with said casing, positioned for operating said actuating mechanism when said casing is assembled with said base; and means whereby said casing and

said base may be assembled in only one relative rotative position.

25. An electric switch, comprising: an insulating base; a pair of terminals mounted on and projecting from said base; an insulating member fitting between said terminals; and means for securing said insulating member to said one of said terminals.

26. An electric switch, comprising: a casing, having a portion providing an aperture; a mounting plate for said switch, provided with an aperture through which said portion of said casing

extends; a base, closing said casing aperture; and said casing being provided with means constructed and arranged to embrace opposite surfaces of said mounting plate, and to embrace opposite surfaces of said base.

27. An electric switch, comprising: a terminal having a plane portion provided with lugs extending laterally in opposite directions from opposite margins of said portion, said portion and said lugs being integrally formed from sheet metal stock; and a switch member pivoted on said lugs.

HARRY A. DOUGLAS.
